US00D946382S

(12) **United States Design Patent** (10) **Patent No.:** **US D946,382 S**
Graykowski et al. (45) **Date of Patent:** **** Mar. 22, 2022**

(54) **CARABINER**(71) Applicant: **Milwaukee Electric Tool Corporation**,
Brookfield, WI (US)(72) Inventors: **Anthony S. Graykowski**, Belgium, WI
(US); **Andrew G. Wagner**, Lisbon, WI
(US); **Derek Rose**, Menomonee Falls,
WI (US)(73) Assignee: **Milwaukee Electric Tool Corporation**,
Brookfield, WI (US)(**) Term: **15 Years**(21) Appl. No.: **29/727,535**(22) Filed: **Mar. 11, 2020****Related U.S. Application Data**(62) Division of application No. 29/685,903, filed on Apr.
1, 2019, now Pat. No. Des. 882,378, which is a
division of application No. 29/634,242, filed on Jan.
19, 2018, now Pat. No. Des. 848,823.(51) **LOC (13) Cl.** ..... **09-06**(52) **U.S. Cl.**USPC ..... **D8/356**(58) **Field of Classification Search**USPC D8/356, 354, 349, 367
CPC . B63B 21/045; A62B 35/0081; B60P 7/0823;
H04R 1/1033; A44B 13/0029

Primary Examiner — Cynthia R Underwood*(74) Attorney, Agent, or Firm* — Reinhart Boerner Van
Deuren s.c.(57) **CLAIM**We claim the ornamental design for a carabiner, as shown
and described.**DESCRIPTION**FIG. 1 is a perspective view of the carabiner according to the
invention;

FIG. 2 is a right side view of the carabiner of FIG. 1;

FIG. 3 is a left side view of the carabiner of FIG. 1;

FIG. 4 is a back side view of the carabiner of FIG. 1;

FIG. 5 is a front side view of the carabiner of FIG. 1

FIG. 6 is a top side view of the carabiner of FIG. 1; and,

FIG. 7 is a bottom side view of the carabiner of FIG. 1.
